UNITED STATES PATENT OFFICE.

WILLIAM V. SCHNUR, OF GLENCOE, ILLINOIS, ASSIGNOR TO P. BECKER & COMPANY, OF CHICAGO, ILLINOIS, A CORPORATION OF ILLINOIS.

WARDROBE-TRUNK.

1,162,258.

Specification of Letters Patent. Patented Nov. 30, 1915.

Application filed August 31, 1914. Serial No. 859,455.

To all whom it may concern:

Be it known that I, WILLIAM V. SCHNUR, a citizen of the United States, residing at Glencoe, in the county of Cook and State of Illinois, have invented certain new and useful Improvements in Wardrobe-Trunks, of which the following is a specification.

My invention relates to wardrobe trunks and has for a primary object to provide for supporting the clothes hangers on which the garments contained in the trunk are hung, a strong, rigid and durable structure which may be extended out beyond the wardrobe section of the trunk when the latter is opened, to facilitate access to the clothing supported thereon.

A further object is to so construct such supporting structure that when collapsed within the wardrobe section it will act as a brace or reinforcement of the same.

A further object is to provide a supporting structure of this character which will be inexpensive to manufacture and may be conveniently and cheaply put in place in the trunk.

In the drawings Figure 1 is a side elevation of a wardrobe trunk furnished with a garment-supporting structure embodying my invention, the trunk being closed and a part of the wardrobe section shown as broken away to expose the interior thereof. Fig. 2 is a front elevation of the trunk with the sections in their open position. Fig. 3 is a fragmentary vertical sectional view of the upper section of the trunk shown in Figs. 1 and 2. Fig. 4 is a horizontal section thereof showing the supporting structure in partially extended position. Fig. 5 is a fragmentary view in perspective of the supporting structure.

Like characters of reference designate like parts in the several figures of the drawings.

A indicates a garment hanger of any desired type, suitable for use in wardrobe trunks and provided at its ends with rail yokes 10. Within the body of the trunk the hangers are supported by a pair of channel rails 11 and 12, upon the upper side of which the rail yokes 10 bear.

A pair of horizontal guides 13 and 14 are secured to opposite sides of the wardrobe section B of the trunk. These guides are preferably composed of channel-shaped

metal strips having inturned flanges 15 55 adapted to retain slides 16 and 17. The channel rails 11 and 12 are secured to the slides 16 and 17 respectively, by means of shouldered rivets 18 which, while rigidly connecting the rails and slides, serve likewise to maintain them in suitable spaced relation. The guides 13 and 14 are fixed to the wall of the trunk by means of brackets 19, two of such brackets preferably being employed one adjacent each end of the 60 guide. These brackets, in addition to supporting the guides, form stops which, by contact with the rivets 18, limit the travel of the slides 16 within the guides 13 and 14. By means of this construction, as shown in 70 Figs. 4 and 5, the rails 11 and 12 may be extended forwardly of the forward edge of the wardrobe section. The channel rails 11 and 12 have their open sides facing outwardly toward the sides of the trunk and 75 their upper and lower flanges at their forward ends are extended beyond the end of the main web of the rail in each instance to form lugs 20 (see Figs. 4 and 5). Hinged by means of vertical pivots 21, borne by the 80 lugs 20, to the rails 11 and 12 respectively, are two channel-shaped rail extensions or arms 22 and 23, the outer extremities of which meet and are secured together by means to be described, when folded over; 85 the two arms forming in such case a rigid brace between the rails 11, 12. Preferably the rear ends of the rails 11, 12, are joined by a brace 24, which has its ends bent forward and riveted to the main webs of the 90 channels 11 and 12.

An important feature of the present invention is the structure of the hinges, by which the rails 11 and 12 are connected respectively with the arms 22 and 23. A solid 95 block of metal 25 fitting closely within the channel of each arm, is riveted to the arm at 26 and extends between and beyond the lugs 20, as shown at 27. The vertical pivots 21 pass through the blocks 25 and the forward 100 ends of the lugs 20, which are rounded at their inner corners to permit pivotal movement of the arms with respect to the rails. The extensions 27 of blocks 25 are formed to fit snugly within the channels of the rails 11 105 and 12 and against the central webs thereof so that, in the open or extended position of the arms, as shown in Fig. 5, each arm is

perfectly rigid with the rail to which it is pivoted. In the closed position of the arms 22 and 23, as shown in Fig. 4, the blocks 25 bear against the outer edges 28 (see Fig. 5) of the main webs of the rails 11 and 12.

Adjacent the end of each arm is a vertical keeper 29 and in each arm and slightly spaced from the keeper 29 is a second keeper 30. Preferably the upper ends of the keepers 29 are extended upwardly beyond the upper flanges of the arms, as at 31, to provide stops for preventing the garment-hangers from sliding off the ends of the rails. One of the arms, the arm 22 for example, carries a bolt 32 adapted to fit snugly in the channel formed by the arms and between the keepers 29-30 and the central webs of the arms. A handle 33 is formed upon the inner end of the bolt and a stop 34 is provided within the channel of the bolt carrying arm. The stop 34 is positioned such a distance from the keeper 30 as to prevent the dislodgment of the bolt from the arm by which it is carried. By these arrangements the arms or rail extensions 22 and 23, when folded over and locked, together with the other parts of the garment supporting means, form a rigid bracing structure which reinforces the wardrobe section of the trunk.

It will be noted that in the closed and bolted position of the arms, a rigid rectangular frame is formed, which is slideable from its innermost position within the wardrobe section of the trunk to a position of extension beyond the forward edge thereof. The rigidity of the frame thus formed, which, of course, may support garments of considerable weight in the aggregate, facilitates pulling out the frame. By slideably mounting the rails 11-12, the whole body of clothing may be moved away from the back wall of the trunk when set up as a wardrobe. This is conveniently done by pulling forward on the locked extensions 22, 23. When a particular garment is wanted the extensions may be unlocked and folded out and the hangers in the front of the trunk pulled out on the extensions until the desired garment is accessible.

Heretofore it has been customary to hinge the upper end of the wardrobe section in trunks of this type to the body portion of such section, in order to provide more ready access to the clothing in the back of the trunk. This construction greatly weakens the upper end of the trunk. By use of the supporting structure of my invention the necessity for hinging the end of the wardrobe section so that it may be folded back is entirely obviated.

In the accompanying drawings and in the foregoing description, is set forth the preferred embodiment of my invention, but it is obvious that one skilled in the art may make

modifications thereof without departing from the spirit of the invention.

I claim:

1. In a wardrobe trunk a garment supporting structure comprising a pair of rail sections slidably mounted in the trunk so as to move in the direction of their length and a pair of extensible rail sections hinged to the extremities of said slideable sections at points which are fixed with respect to said slideable sections; the upper surfaces of said hinged sections being in the same plane with the upper surfaces of said slideable sections so as to provide a pair of continuous bearing surfaces spaced apart for slideably supporting the opposite ends of garment hangers. 70

2. In a wardrobe trunk, a garment-supporting structure comprising a pair of channel-shaped slideable rail sections, and a pair of extension rail sections carried respectively upon the forward ends of said slideable rail sections by means including a pair of lugs formed upon the forward end of each slideable rail section, a block carried upon the adjacent end of each extension rail section, extending between and beyond said lugs, and which fits closely within the channel of the slideable rail section when the sections are in alinement, and a pivot traversing the block and secured at its ends in the lugs. 90

3. In a wardrobe trunk, a garment-supporting structure comprising a pair of rail sections and means for slideably mounting said sections within the trunk, comprising a pair of channel shaped guides, an independent slide mounted within each guide, and means for rigidly securing each rail in spaced relation to one of said slides. 100

4. In a wardrobe trunk, a garment-supporting structure comprising a pair of slideable channel rail sections, a pair of extension channel rail sections mounted respectively upon the forward ends of said slideable rail sections and foldable into alinement with each other, and means for locking said extension rail sections together when in alinement, comprising a pair of keepers traversing the channel of each extension rail section adjacent the free end thereof, said keepers being spaced from each other and from the main web of the rail section, and a bolt carried by one section, slideable into engagement with the other section, and fitting between the side flanges of each section and between the keepers and the main web of each section. 110

5. In a wardrobe trunk, a garment-supporting structure comprising a pair of longitudinally slideable rail sections, a pair of extension rail sections respectively hinged upon the forward ends of the slideable section with their upper surfaces in the same plane with the upper surfaces of the slideable rail sections and foldable into alinement with each other, means for locking 120

said extension sections together when in alinement, and a brace connecting the rearward ends of said slidable rail sections.

6. In a wardrobe trunk, a garment-supporting structure comprising a pair of channel guides, a pair of brackets for each guide positioned adjacent opposite ends thereof and supporting the guides within the trunk, a slide mounted within each channel guide, 10 a pair of channel shaped slidable rail sections each being rigidly secured in spaced relation to one of said slides, a pair of channel shaped extension rail sections carried respectively on the forward ends of 15 said slidable rail sections by means including a pair of lugs formed upon the forward end of each slidable rail section, a block secured to the adjacent end of each extension rail section and extending therefrom 20 between and beyond said lugs and fitting the channel of the slidable rail section, and a pivot traversing the block and secured at its ends in the lugs; said extension rail sections being foldable into alinement; 25 means for locking said extension section together when in alinement comprising a pair of keepers spaced from each other and from the main web of the extension section traversing the channel thereof near the free end 30 of the section, and a bolt carried by one of said sections and fitting the space formed between the side flanges of the sections and between the keepers and the main web of the sections; and a brace rigidly connecting 35 the rearward ends of said extension rail sections.

7. Two channels and means for hinging them together, comprising a pair of lugs protruding from the ends of the side flanges 40 of one channel, a block fitting both channels, secured to one and extending between and beyond said lugs, and a pivot mounted by its ends in the lugs and traversing the block.

- 45 8. Two channels, and means for hinging them together, comprising a pair of lugs protruding from the side flanges of one channel, a block fitting both channels secured to one and extending between and beyond said lugs, and a pivot mounted in the lugs and traversing the block.

9. In a wardrobe trunk, a garment supporting structure comprising a pair of channel rail sections, and means for hinging one 55 section to the other and limiting the hinging movement to approximately a quarter of a circle, comprising a block fixedly positioned

within the channel of one of said sections and adapted to fit snugly within the channel of the other section when said sections are 60 in alinement.

10. In a wardrobe trunk, a garment supporting structure comprising a pair of channel rail sections positioned with their main webs in vertical planes, and means for hinging one section to the other and limiting its hinging movement to approximately a quarter of a circle, comprising a block fixedly positioned within the channel of one 65 of said sections, and a pintle vertically positioned in the other section and traversing the block, said block being adapted to extend within and fit snugly into the channel of the pintle carrying section when said sections are in alinement. 75

11. In a wardrobe trunk, a garment supporting structure comprising guides on the side of the trunk, slides mounted to move therein, rail sections fixed to said slides so as to be movable longitudinally in and out 80 of the trunk, extension rail sections hinged to the ends of the first named rail sections respectively, so as to stand in alinement therewith when extended, and means for fastening the ends of said extension sections 85 together when folded.

12. In a wardrobe trunk, a garment supporting structure comprising channel guides fixed to the sides of the trunk with their open sides facing inwardly, slides in said 90 guides, rail sections fixed to said slides, and extension rail sections hinged to the ends of the first named rail sections with their upper surfaces in the same planes with the upper surfaces of said first named rail sections, and means for fastening the ends of 95 said extension sections together when folded.

13. In a wardrobe trunk a garment supporting structure comprising a pair of rail sections slidably mounted in the trunk so 100 as to move in the direction of their length, and a pair of extensible rail sections hinged to said slidable sections; the upper surfaces of said hinged sections being in the same plane with the upper surfaces of said slidable sections so as to provide a pair of continuous bearing surfaces spaced apart, for 105 slidably supporting the opposite ends of garment hangers.
